UNITED STATES PATENT OFFICE.

JOHN P. DORAU, OF HORICON, WISCONSIN.

IRONING BOARD.

Application filed May 14, 1923. Serial No. 638,859.

This invention relates to improvements in ironing boards, and more particularly to ironing boards which may be folded when not in use.

It is the principal object of the present invention to provide an ironing board which may be easily folded to a closed position in a very simple manner so as to occupy but a minimum amount of space when not in use.

10 A further object of the invention is to provide a foldable ironing board having a simple and effective means for locking the legs when the board is in either open or folded position.

15 A further object of the invention is to provide a foldable ironing board which forms a very rigid and steady support when the legs are locked in open position.

20 A further object of the invention is to provide a foldable ironing board which is of very simple construction, is strong and durable, and is well adapted for the purpose described.

25 With the above and other objects in view, the invention consists of the improved ironing board and its parts and combinations as set forth in the claims, and all equivalents thereof.

30 In the accompanying drawing in which the same reference characters indicate the same parts in all of the views:

Fig. 1 is a side view of the improved foldable ironing board shown in open position;

35 Fig. 2 is an inverted plan view thereof;

Fig. 3 is a fragmentary side view of a modified form of the invention with the parts shown in open position; and

40 Fig. 4 is a fragmentary front end view thereof.

Referring to the drawing, the numeral 8 indicates the ironing board proper which may be of any desirable shape, but is preferably of rectangular form, except the rear end portion 8' which is tapered. A bracket 9, with a U-shaped opening 10 therein, is mounted longitudinally on the under side of the board near the front end thereof, and the upper end portions of a pair of legs 11 are pivotally connected to the outside faces of the bracket by a pivot bolt 12. Said upper end portions are cut diagonally as indicated by the numeral 11' so that when in open position they will bear flatly against the underside of the board and form a stop for the outward movement of said legs.

The legs diverge from each other outwardly from the bracket, and medially of their length are connected together by a brace member 13 and a brace rod 14.

50 A third leg 15, diverging from the legs 11 when the legs are in open position as shown, has its upper end portion lodged within the U-shaped opening 10 of the bracket 11 and is pivotally held therein by means of the pivot bolt 12. Medially of the length of said leg, a pair of links 16 are pivotally connected by means of a pivot bolt 17 and the other ends of said links are pivotally connected to a second link member 18, the inner end of which is hingedly secured, as at 19, to the underside of the board 8 near the tapered end portion 8' thereof. A pair of rods 20 have their inner ends bent about a bolt 21 which connects members 16 to member 18, and the other ends of said rods are pivotally secured to a lever or crank 22. Said crank is of bifurcated form and has its end portions extending through the legs 11 to form a pivotal connection therewith, as at 23.

55 To unfold the ironing board, leg 15 is first swung away from the board. Then the legs 11 are moved away from the board and at the same time, lever or crank 22 is moved toward the extremities of legs 11. This movement of the lever or crank will pull on rods 20 which in turn pull link members 16 and 18 until their point of connection 21 is out of alignment with the centers 17 and 19, as shown, and rod 14 will drop into a

60 groove 24 provided therefor in member 18 and all of the parts will be securely locked in open position. The reverse operation 65 folds the ironing board and the crank is first moved to shift the point of connection to the other side of the centers 17 and 19. The legs 11 are then folded toward the board and the leg 15 is next folded and the links 16 and 18 pivot with respect to each

70 other to the position shown in Fig. 2. When the legs are in folded position, the parts will lie in a plane approximately parallel to the board with the leg 15 and links 16 folded upon link 18 and all within the space enclosed by legs 11. A notched groove 25 provided in member 18 receives brace rod 14. When so folded, the ironing board may be stored away in a comparatively small 75 space.

80 In the modified form of the invention shown in Figs. 3 and 4, the legs 11 and a

pair of shorter legs 15' are pivotally connected to a U-bracket 9' by means of a pair of pivot bolts 12. Secured to the under-side of the board 8 by means of a hinge 19 is a crank 22' of elongated form and said crank is pivotally secured medially of its length, as at 26, to a pair of links 16', the other ends of said links being pivotally secured to legs 15', as at 27. When the legs 10 are in open position, the lower end of the crank will drop into a groove 28 formed in a brace 13, thereby locking the parts in open position. A pair of brace rods 20 are also provided and have one pair of ends 15 thereof formed with eyes through which the pivot bolt 27 extends. Said rods extend to the other pair of legs 11 and pass through eye-bolts 28 provided therein and when the legs are in open position the bent ends 29 20 of said rods will bear against said eye bolts and serve as stops. When the legs are in folded position, all of the parts will lie against the board approximately parallel thereto and the eye bolts 28 permit a sliding 25 movement of said rods as the legs 15' are moved toward the board.

From the foregoing description, it will be seen that the foldable ironing board is of very simple construction, and may be 30 easily opened for use, and when so opened, the parts are effectively locked in position.

What I claim as my invention is:

1. A foldable ironing board, comprising a board member, legs pivotally connected to the bottom portion thereof, link means comprising a pair of pivotally connected members and connected to one of the legs and to the board member, rods connected to said link means, and a crank member connected 40 with others of said legs and with the rods and limited in movement.

2. A foldable ironing board, comprising a board member, legs pivotally connected to the bottom portion thereof, pivotally connected link members connected to one of the legs and to the board member, a crank member associated with a pair of said legs, and rods connected with said link members at their point of pivotal connection and 50 with said crank member, said crank member

being limited in movement and connected to said link means by said rods to lock said legs in open supporting position.

3. A foldable ironing board, comprising a board member having a bracket on its under side, a pair of legs and a single leg pivotally connected to said bracket member, said single leg and the pair of legs diverging from each other when in open position and also foldable upon each other to a position parallel to said board, link means connected to said single leg and the board, rods connected to said link means, and a cranked member pivotally connected to said pair of legs and to said rods to move said link means, said cranked member being limited in movement.

4. A foldable ironing board, comprising a board member, a pair of legs and a third leg pivotally connected to the bottom portion thereof, a link hingedly connected to said board, links pivotally connected to said third leg and said first mentioned link, a cranked member limited in movement and connecting the lower portions of said pair 75 of legs, and connecting rods extending from the pivotal connection of said links to said cranked member.

5. A foldable ironing board, comprising a board member, a pair of legs and a third leg pivotally connected to the bottom portion thereof adjacent each other, a link hingedly connected to said board and having a groove therein, links pivotally connected to said third leg and said first mentioned link, a cranked member limited in movement and pivotally mounted in said pair of legs, and connecting rods extending from the pivotal connection of said links with each other to said cranked member, said pair of legs having a brace rod insertable in the groove in said first mentioned link to lock said legs in open position when said connecting rods are moved by said cranked member and the pivotal connection of said links is moved thereby to a position out of alignment.

In testimony whereof, I affix my signature.

JOHN P. DORAU.
